Primary Examiner — Steven J Czyz(74) *Attorney, Agent, or Firm* — Andrus Intellectual Property Law, LLP(57) **CLAIM**

The ornamental design for a handle for a hiking stick, as shown and described.

DESCRIPTION

FIG. 1 is a front perspective view of a handle for a hiking stick according to my new and ornamental design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view of the handle for a hiking stick shown in use with environment.

The evenly-spaced broken lines depict portions of the article and environment that form no part of the claimed design; the dash-dot-dash lines represent the boundary of the claimed design and form no part of the claimed design.

1 Claim, 5 Drawing Sheets(56)
